UNITED STATES PATENT OFFICE

2,670,432

LAMP SOCKET AND HARP ASSEMBLY

George B. Benander, Oaklawn, R. I., assignor to
General Electric Company, a corporation of
New York

Application October 24, 1951, Serial No. 252,935

2 Claims. (Cl. 240—148)

1

This invention relates to electric portable lamps and in particular to an improved lamp harp and the means for securing the same to a lamp socket.

By lamp harp is meant a wire loop which extends above a lamp socket to provide support for a lamp shade. The harp conventionally has two free ends which are anchored to a lamp socket and a pivoting device of some sort at the top to provide pivotal support for a lamp shade. An electric bulb may be positioned in the socket and within the harp.

The means for securing my improved lamp harp serves a dual function of locking the harp in position and holding two halves of a lamp socket together.

Lamp harps, if assembled on a lamp before shipment, necessitate the use of a carton several inches longer than that which would be required if the lamp harp were not assembled. Accordingly, it is an object of this invention to provide an improved lamp harp including means for assembling the same wherein the lamp harp can be assembled on the lamp socket by the ultimate consumer.

It is a further object of this invention to provide a combined device which supports a lamp harp and which secures together the halves of a lamp socket.

It is a still further object of this invention to provide an improved securing device for a portable lamp harp wherein the free end of the harp can be snapped into position in such a manner that they are secured in place until the lamp socket is disassembled.

Further objects and advantages of this invention will become apparent and the invention will be more clearly understood from the following description referring to the accompanying drawing and the features of novelty which characterize this invention will be pointed out with particularity in the claims annexed to and forming a part of this specification.

Briefly, this invention comprises the combination of a harp having a pair of free ends with detents positioned on each end and a lamp socket having a pair of molded bushings which are each formed from two halves. The bushings have axial bores including notches molded therein for engaging the detents on the ends of the lamp harp. A resilient securing device holds the socket halves together in such a manner that they will spread when the detent portion of the harp is forced through the bushing and the socket halves will resiliently be brought back into mating engagement when the detent portion of the lamp

2

harp engages the corresponding notches in the bushing.

In the drawing, Fig. 1 is a front elevation of an improved lamp socket and harp including a shade shown in dotted outline; Fig. 2 is a front elevation of a portion of the lamp socket shown in Fig. 1 including one end of the harp inserted in one bushing and with the other end of the harp about to be inserted into a corresponding bushing; Fig. 3 is a side view taken along the line 3—3 of Fig. 2 showing the detent on one harp end inserted into its respective notches while Fig. 4 is a top elevation of one of the bushings of the lamp socket shown in the other figures.

In the drawing, lamp 1 is shown as comprising a socket 2 mounted on a base 3. The socket supports a bulb 4, and a harp 5, which in turn supports the shade 6.

The construction of the lamp including the means for mounting socket 2 on base 3 is more completely described in my copending application Serial No. 248,621, filed September 27, 1951, now Patent No. 2,652,548, assigned to the same assignee as the present application and the lamp socket itself including its two halves is described more completely in my copending application Ser. No. 182,243, filed August 30, 1950, now Patent No. 2,652,485, also assigned to the same assignee as the present application but briefly, the lamp socket 2 comprises two mating halves 7 and 8 which are united to form a somewhat cylindrical outer shell. The lamp socket itself is made of one of the phenolic or urea molding compounds or it might be made from any suitable material approved for this use by the Underwriter's Laboratories.

The lamp socket 2 is molded to have a pair of bulges or bushings 9, 10 each of which has a longitudinal split such as that shown in Fig. 3 wherein the bulge 10 is shown comprising the bulge halves 11 and 12. Each of the bulge halves 11 and 12 has a notch 13, 14 respectively, formed in it. The notches are positioned in the periphery of a bore 15 which is defined by the bulge halves 11, 12. In the wall of bore 15 are opposed vertically extending guide grooves 15a which, at their lower end, communicate with notches 13 and 14, and at their upper end merge into a beveled wall 15b at the outer end of bore 15.

With such a structure a pair of molded socket halves are united along a common seam to form an aperture for receiving electric bulb 4 and a pair of bores 15 which are defined one each by the bulges 9, 10. The mating halves of the

socket and bulges are then held together by a pair of spring clips 16, 17.

The spring clips, one of which is shown in Fig. 4, each comprise a U-shaped strap of resilient material having a pair of ears 18 and 19 which fit into corresponding notches or grooves 20 and 21 located at the junction of the bulges 9, 10 and socket 2. The spring clips are slid axially along the bulges so that the ears 18, 19 slide, preferably upwardly, in the grooves 20, 21 until the spring clips are positioned substantially at the top of the bulges as shown in Fig. 1. With such a structure the socket is assembled in such a manner, that its halves may be spread apart slightly against the resiliency of the clips 16, 17 whereupon after the spreading pressure is released, the clips 16, 17 will reassemble the socket parts in mating relationship.

Lamp harp 5 is formed in any desired shape and preferably it has a pair of free ends 22, 23 as shown in Fig. 2. The free ends 22, 23 are inserted into bores 15 within bulges 9, 10 respectively. Accordingly, the lamp harp 5 is made of a material which, after being preformed, will be rigid enough to support a shade and be supported by the bulges 9, 10.

The lower portion of the harp free ends 22, 23 are each provided with detents 25, 26. These detents may be swaged or otherwise formed to have a shape which will engage the notches 13, 14 in the bulge halves 11, 12.

With such a structure when the lamp harp 5 is inserted into the socket, its free ends 22, 23 are inserted into the bulges 9, 10 respectively. The detents 25, 26 force the bulge halves 11, 12 apart in opposition to the resiliency of clips 16, 17 until the detents 25, 26 fit into the notches 13, 14 whereupon the bulge halves 11, 12 are again brought back to mating relationship by the clips 16, 17. Accordingly, it is a simple matter for the ultimate consumer to take the lamp harp 5 and insert it into the lamp socket 2. In inserting the harp ends into the bores, they are guided by the detent following down the guides grooves 15a. The bevel at the upper end of the bore assists in initially guiding the harp ends into the grooves.

When inserted as described, the harp is fixedly positioned within the bulges 9, 10 so that it cannot be removed unless the bulge halves 11, 12 are spread sufficiently to allow the detents 25, 26 to be withdrawn through the bores 15.

It has been found that the combination of the spring clips 16, 17, and the detents 25, 26 with the notches 13, 14, provides a dual function device wherein the free ends 22, 23 of the harp are supported in the bores 15 and the spring clips 16, 17 hold the socket halves together.

To provide support for lamp shade 6, a double swivel 24 is positioned at the top of the lamp harp 5 whereby the lamp shade 6 can be tilted in two planes; that is, it can be tilted into or out of the plane of the drawing, or it can be tilted in the plane of the drawing.

Modifications of this invention will occur to

those skilled in the art and it is desired to be understood, therefore, that this invention is not to be limited to the particular embodiment disclosed but rather it is intended to cover all modifications which are within the true spirit and scope of this invention.

What I claim as new and desired to secure by Letters Patent of the United States is:

1. In combination, a lamp socket having an outer shell split longitudinally to form two shell parts, bulges integral with the shell parts at the seam between such parts which extend longitudinally along the opposed sides of the shell and are contoured to provide vertically extending bores open at their upper end, said bulges being split longitudinally in line with the split between the shell parts to provide complementary bulge members integral with each shell part, recessed walls at the lower ends of said bores which define notches which extend into the walls of the bores at right angles to the plane of the split between the bulge members, spring clips clamped over said bulges to yieldingly hold the shell parts and bulge members together, and a harp having free ends positioned in said bores, said harp ends having diameters equal to the diameters of said bores and outwardly projecting detents positioned in said notches, said spring clips being adapted to yield to permit separation of the shell parts and bulge members so that the harp ends may be pushed down through the bores to bring the detents into said notches.

2. A lamp socket having an outer shell split longitudinally to form two shell parts, bulges integral with the shell parts at the seam between such parts which extend longitudinally along the opposed sides of the shell and are contoured to provide vertically extending bores open at their upper ends, said bulges being split longitudinally in line with the split between the shell parts to provide complementary bulge members integral with each shell part, recessed walls at the lower ends of said bores which define notches which extend into the walls of the bores at right angles to the plane of the split between the bulge members, and spring clips clamped over said bulges to yieldingly hold the shell parts and bulge members together, whereby said shell parts and bulge members may be moved apart by a harp having free ends provided with outwardly projecting detents to attach a harp to the lamp socket with the detents positioned in said notches.

GEORGE B. BENANDER.
